UNITED STATES PATENT OFFICE

152,845

DESIGN FOR A BROOCH OR SIMILAR ARTICLE

Marvin J. Wakeman, Brooklyn, N. Y.

Application November 30, 1948, Serial No. 149,878

Term of patent 3½ years

(Cl. D45—19)

To all whom it may concern:

Be it known that I, Marvin J. Wakeman, a citizen of the United States, residing at 58 Pierrepont Street, Brooklyn, in the county of Kings and State of New York, have invented a new, original, and ornamental Design for a Brooch or Similar Article, of which the following is a specification, reference being had to the accompanying drawing, constituting a part thereof:

Fig. 1 is a top plan view of a brooch or similar article, showing my new design.

Fig. 2 is a front elevational view.

Fig. 3 is a side elevational view.

I claim:

The ornamental design for a brooch or similar article, substantially as shown.

MARVIN J. WAKEMAN.
